W. J. GROTH

FIREPLACE HEATER

Filed March 26, 1923

INVENTOR.
William J. Gröth

BY R. W. Smith
ATTORNEY

UNITED STATES PATENT OFFICE.

WILLIAM J. GROTH, OF LOS ANGELES, CALIFORNIA.

FIREPLACE HEATER.

Application filed March 26, 1923. Serial No. 627,605.

To all whom it may concern:

Be it known that I, WILLIAM J. GROTH, a citizen of the United States, residing at Los Angeles, county of Los Angeles, State 5 of California, have invented new and useful Improvements in Fireplace Heaters, of which the following is a specification.

This invention is a heater for use in connection with an open fireplace, and it is the 10 object of the invention to provide an air chamber or conduit receiving fresh air from a suitable source, and arranged so that the heat from the fireplace is directed against said chamber in order to heat the air passing 15 through the same, the heated air being discharged at a suitable point.

It is a further object of the invention to provide an air chamber positioned at the rear and upper portion of the fireplace, and 20 extending across the smoke flue for discharge into a room at a point above the fireplace, the portion of the air chamber extending across the smoke flue being arranged to permit the smoke being readily drawn into 25 said flue, and said portion of the air chamber cooperating with suitable closure means to control the passageway through said flue, and thereby form a damper for the fireplace.

The invention will be readily understood 30 from the following description of the accompanying drawings, in which:

Fig. 1 is a front elevation of a fireplace having the improved heater mounted therein.

Fig. 2 is a vertical section on the line 2—2 of Fig. 1.

Fig. 3 is a front elevation of the heater unit.

Fig. 4 is a fragmentary detail section on 40 the line 2—2 of Fig. 1.

A fireplace having the improved heater mounted therein is illustrated in the drawings as a brick structure built against the outer wall 1 of a house. The fireplace includes a rear wall of substantial thickness, and sides 2 and top 3 extending outwardly from the rear wall and forming a usual fire space or recess 4 in the lower portion of the fireplace structure at the front thereof.

50 The lower portion 5 of the rear wall of the fireplace structure has a vertical front surface, and the upper portion 6 of said wall has a front surface slanting upwardly and forwardly. The sides of the fireplace struc-

ture are recessed as shown at 7 at their junction with wall 6, and a smoke flue 8, the width of the fire space 4 and the recesses 7, extends upwardly for a short distance through the fireplace structure, at the top of the fire space 4 and in front of wall 6, 60 said flue then extending rearwardly through the fireplace structure over the top of wall 6, and terminating in a vertical chimney 9 positioned against wall 1 of the house.

A vertical flue 10, preferably only partly 65 the width of fire space 4, is formed in wall 5, said flue opening at its upper end into the fire space at a point spaced below the base of wall 6, and the lower end of the flue extends rearwardly through wall 5 and 70 through wall 1 of the house, so as to open to the outer atmosphere, for the admission of fresh air.

A flue 11 of the same width as smoke flue 8, is open to the front vertical portion of the 75 smoke flue, and extends upwardly through the fireplace structure and thence horizontally outwardly through the top portion of the fireplace structure, so as to open into the room in which the fireplace is built, at 80 a point spaced above the fire space 4.

The heater mounted in the fireplace as thus described, is a box-like structure having front and rear walls 12 and 13, and side walls 14 and upper end wall 15 connecting said side walls, the lower end of the structure being open.

This box-like structure is mounted against wall 6 with its sides received in recesses 7, the front lower edge of the structure resting upon a ledge 16 formed upon wall 5 at the base of flue opening 10, so that the lower open end of the structure is received against wall 5 and over the opening of flue 10, for discharge of fresh air from said flue into 95 the heating box.

The upper end wall 15 of the heating box is at the upper end of wall 6 and at the base of the smoke flue, and transversely spaced pipes 17 project beyond wall 15 across the 100 smoke flue to the end of flue 11 which opens into said smoke flue, the spacing of said pipes permitting of the free passage of smoke through flue 8 between said pipes.

A plate 18 is mounted upon the ends of 105 pipes 17 and is adapted to fit in the end of flue 11 in horizontal position, and an angle iron 29 extends across the fire space 4, with

one arm thereof against the masonry at the top of said fire space, and the other arm of said angle iron against the front wall of the vertical portion of smoke flue 8, the edge 5 of plate 18 being adapted to be hooked over the angle iron as shown at 19, in order to support the upper end of the heater in position within the fireplace. A plate 20 preferably extends upwardly from the rear 10 edge of plate 18 and is received against the rear wall of the vertical portion of flue 11.

It will thus be seen that the improved heater is a unitary structure including the box-like heating chamber, pipes 17, and 15 plates 18 and 20. The heating unit may be readily mounted in a fireplace, and in operation, fresh air is drawn into the heating chamber of the device through flue 10, and is heated by the fire, the heated air passing 20 through pipes 17 into flue 11 from whence it is discharged into the room. The smoke from the fireplace is drawn through flue 8 into chimney 9, and is prevented from entering flue 11 by plate 18 closing the 25 latter.

A damper is preferably provided for the smoke flue of the fireplace, said damper comprising a closure plate cooperating with pipes 17 which extend across the smoke 30 flue, to regulate the opening through said flue. As an instance of this arrangement, a plate 21 is hinged at 22 to the rear edge of end wall 15 of the heating box, said plate being adapted to be swung forwardly 35 and downwardly so as to rest upon pipes 17 and close the passage through the smoke flue, or to be swung upwardly and rearwardly to any desired degree, so as to form an opening of desired size through 40 the flue.

The damper plate 21 is preferably actuated by a rod 23 extending forwardly to the front of the fireplace below the top wall of fire space 4. This rod may be pivoted to 45 plate 21 as shown at 24, and a handle 25 is provided at the front end of the rod. The portion of the rod adjacent the handle is notched as shown at 26, with said notches adapted to be engaged by a supporting 50 bracket 27 depending from the masonry of the fireplace, in order to adjustably position the operating rod and thereby regulate the damper opening.

I claim:

1. A fireplace structure having a fire space, a smoke flue at the top of said fire space and extending through said fireplace structure; an air conduit in said fire space and having a fresh air inlet, pipes extending across said smoke flue from said air conduit to form a hot air discharge, and a damper comprising a closure plate hinged to said air conduit at its junction with said pipes and mounted in said smoke 65 flue extending across said pipes, said plate

being adapted to be swung away from said pipes to open said smoke flue, and to be swung into position resting upon said pipes for closing said smoke flue.

2. An air heater for a fireplace comprising a heating box having a fresh air inlet at its base, discharge pipes transversely spaced and projecting from the upper end of said box, and a damper plate hinged to said box at its junction with said pipes 75 and adapted to extend across said pipes and the spaces between the same, said damper plate being adapted to be swung away from said pipes to open the damper, and to be swung into position resting upon said pipes 80 for closing the damper.

3. The combination of a fireplace structure including a vertical rear wall having a fresh air opening therethrough and terminating at its upper end in a forwardly and upwardly inclined wall, and an air heater comprising a box having a hot air discharge at its upper end and an open lower end angularly disposed with relation to the sides 85 of said box, whereby said lower end is adapted to overlie said fresh air opening and fit snugly against the vertical wall of said fireplace.

4. The combination of a fireplace structure including a vertical rear wall having a fresh air opening therethrough and terminating at its upper end in a forwardly and upwardly inclined wall, and an air heater comprising a box having a hot air discharge at its upper end and an open lower end 90 angularly disposed with relation to the sides of said box, whereby said lower end is adapted to overlie said fresh air opening with its lower edge resting upon the lower edge of said opening and the angularly disposed 95 edges of said lower end fitting snugly against the vertical wall of said fireplace.

5. The combination with a fireplace comprising transversely spaced side walls and an inwardly spaced rear wall connecting the same and having transversely extending recesses at the junctions of said rear wall and side walls, of an air heater comprising a box having a hot air discharge and a fresh air inlet at its upper and lower ends respectively, said box being fixed against said rear wall by the sides thereof received in 110 said recesses.

6. The combination of a fireplace structure including a vertical rear wall having a fresh air opening therethrough and terminating at its upper end in a forwardly and upwardly inclined wall having a smoke flue at the upper end thereof extending through said fireplace structure, an air heater comprising a box adapted to be received against said inclined wall and having an open lower end angularly disposed with relation to the sides of said box, whereby 120 said lower end is adapted to overlie said 125 flue.

fresh air opening and fit snugly against the vertical wall of said fireplace, pipes extending across said smoke flue from the upper end of said box to form a hot air discharge, to be swung away from said pipes to open said smoke flue and to be swung into position resting upon said pipes for closing the 10 smoke flue.

⁵ and a damper hinged to said box at its junction with said pipes and mounted in said smoke flue, said damper being adapted

In testimony whereof I have signed my name to this specification.

WILLIAM J. GROTH.
